UNITED STATES PATENT OFFICE

SHOZABURO AKI, OF MILL HILL, LONDON, ENGLAND

BRUSH

Application filed December 7, 1932, Serial No. 646,172, and in Great Britain November 16, 1931.

This invention relates to brushes suitable for personal, animal, or commercial uses and has for its chief object to provide an article which will be hygienic and efficient and which can be readily cleaned and is renewable or replaceable when necessary.

According to the present invention, the head or stock of the brush is composed or consists of a series of separate and separable units or sections each carrying a competent number of bristles or the like. These units are arranged in rows or parallel with each other within an enclosing or surrounding frame wherein they can be secured for use by a sliding, hinged or other lid, flap or closure.

A further object of the present invention is to provide for the exclusion of dust or the like from such brushes when not in use.

Referring to the accompanying drawings:

Fig. 1 is a side elevation of a brush suitable for personal use, constructed in accordance with or embodying the present invention.

Fig. 2 is a plan of the brush illustrated in Fig. 1.

Fig. 3 is a cross sectional elevation on the line 3—3 of Fig. 1.

Fig. 4 is a sectional elevation of a pair of brushes enclosed in a dust etc. excluding casing.

Fig. 5 is a sectional elevation of a modified construction of brush and

Fig. 6 is a sectional elevation showing another modified arrangement.

In the embodiment of the invention illustrated in Figs. 1 to 3; the body or stock of the brush is rectangular in plan, but it may be round, oval or of other desired shape or form.

The bristle-carrying portion or brush proper is comprised of a series of similar units or sections A which are each provided with a single row of bristles B. These units or sections are conveniently rectangular in cross section so that they fit snugly and evenly against or alongside each other. These sections may be made of wood, rubber, ebonite, metal or other appropriate material.

The units A are adapted to fit closely with-

in a skeleton frame C which is of a depth sufficient to accommodate the units A and allow the bristles B to project beyond it, as shown.

At its lower edge, from which the bristles project, the frame C is furnished with an inwardly projecting rim or ledge C¹ upon which the ends of the units A rest.

When these units forming the complete brush, have been assembled within the frame C, they are secured rigidly therein and relatively to each other by a closure D, which in this instance is in the form of a lid, which slides in grooves C² in the sides and one end of the frame C.

By these means the completed brush forms a rigid structure.

When it is desired to clean the brush the lid or closure D can be quickly and easily withdrawn or removed and the units lifted out of the frame C. They can then be separately washed, cleaned or sterilized and returned to the casing. Likewise a worn or defective unit can be interchanged or replaced quickly and easily.

Likewise if it is desired to replace bristle carrying units by wire-carrying units, this operation can be performed simply and speedily.

While the brush is intended chiefly for personal or animal use, brushes having wire in place of hair or like "bristles" may be constructed for use in wool-combing or for other commercial purposes.

In place of a lid or closure, such as shown in Figs. 1-3, the units A may be secured in place in a frame having a fixed top C³ and an open side or end as shown in Fig. 5. In this case the units are pushed into the frame from the open side, which can be closed by a sliding or hinged flap D¹.

When the brush is of oval or similar form see Fig. 6 the lid or closure D may be hinged at d at one end of the frame C and when closed may be secured by a catch D².

When the brush is not in use, it can be secured against infection or the collection of dust by fitting into a casing as shown in Fig. 4.

Conveniently this casing is adapted to hold

two brushes in a compact and handy manner. The casing, see Fig. 4 comprises a frame E open at top and bottom and furnished with inner lips or shoulders E¹. The two brushes 5 are placed within the frame from opposite ends and fit tightly therein so that the stocks or bodies of the brushes form the top and bottom of the casing.

- 10 By forming the bristle portion of a brush in separate and separable sections or units, the brush can be assembled or disassembled quickly and easily, so that each unit can be separately cleaned or sterilized and to a degree not attainable with hitherto known 15 brushes and the time occupied in such operations is greatly reduced. Likewise the life time of a brush is prolonged, since a worn or defective unit can be removed and replaced by a good one.
- 20 Still further, the manufacture of a brush is simplified and cost reduced, since any required forms or sizes of brushes can all be made up from a standard bristle-carrying stock.

25 What I claim is:—

- 30 1. A detachably assembled brush comprising a frame having side walls and a removable top wall, the bottom of said frame being open, the inner lower surface of certain of said side walls being provided with inwardly projecting flanges, a plurality of elongated separable bristle-carrying units having their end portions formed to cooperate with the inwardly projecting flanges of the side walls 35 of the frame, said units being positioned in parallel arrangement in said frame with the bristles projecting through the opening in the bottom of said frame, said removable cover and the inwardly projecting flanges of 40 the side walls of the frame cooperating to retain the bristle-carrying units in assembled relation.
- 45 2. A detachably assembled brush comprising a substantially rectangular frame defined by side walls and open at the top and bottom thereof, a pair of said side walls having inwardly projecting flanges provided at the lower portion thereof, a plurality of elongated separable bristle-carrying units having 50 their ends formed to cooperate with the inwardly projecting flanges of the side walls of the frame, said units adapted to be inserted through the open top of the frame with the bristles extending through the open bottom, with the ends of said units on the inwardly extending flanges and with the body portions of the elongated units arranged parallel to each other, and a removable cover 55 for the top of said frame adapted to cooperate with the inwardly extending flanges carried by the side walls for retaining the bristle-carrying units in assembled position.
- 60 3. A detachably assembled brush comprising a substantially rectangular frame defined by side walls and open at the top and bottom 65

thereof, a pair of said side walls having inwardly projecting flanges provided at the lower portion thereof, a plurality of elongated separable bristle-carrying units having their ends formed to cooperate with the inwardly projecting flanges of the side walls of the frame, said units adapted to be inserted through the open top of the frame with the bristles extending through the open bottom, with the ends of said units on the 70 inwardly extending flanges and with the body portions of the elongated units arranged parallel to each other, a pair of said side walls being provided with longitudinal grooves formed in the inner face adjacent the upper portion thereof, and a removable cover for the top of said frame slidably mounted in said grooves and adapted to cooperate with the inwardly extending flanges carried by the side walls for retaining the elongated bristle-carrying units in assembled position.
